CLAIM

The ornamental design for a wall-mounted light fixture or the like, as shown and described.

DESCRIPTION

FIG. 1 is a top plan view of a wall-mounted light fixture or the like showing my new design;

FIG. 2 is a front elevational view thereof;

FIG. 3 is a bottom plan view thereof;

FIG. 4 is a rear elevational view thereof;

FIG. 5 is a left side elevational view thereof, the right side being a mirror image of that shown; and

FIG. 6 is a vertical cross-sectional view thereof, taken along line 6—6 of FIG. 1.

FIG. 1

FIG. 2

FIG. 3

FIG. 4

FIG. 5
